FIG. 6

FREQUENCY DEMODULATOR

BACKGROUND OF THE INVENTION

1. Field of the Invention

The present invention relates to frequency demodulation methods and apparatus and, more particularly, to the demodulation of frequency modulated (FM) signals which have been recorded in video recording systems.

2. Discussion of the Prior Art

The recording of video information on magnetic recording media, such as tapes, disc or drums, has become increasingly important for the storage and instant replay of televised programs material, the storage and retrieval of documents and the recording of fluoroscopic X-ray images, as well as many other uses. Because of the wide bandwidth requirement of video signals, for example 4 megahertz for monochrome television signals, it is necessary that special techniques be employed for recording the wide band video signals to provide high quality reproduction thereof. A technique commonly used for recording video signals is to frequency modulate a carrier frequency with the video signals and then to record the FM signals. A recording system utilizing a magnetic recording disc may have a typical frequency response extending from approximately 100 Hz. to 5.5 MHz. If a frequency modulation recording technique were used, a carrier frequency would be selected somewhere within the frequency response of the recording disc and this carrier modulated according to the video information in a video waveform to be recorded, so that, for example, the black level of a scene would be represented by a frequency of 5.5 megahertz while a frequency of 4 megahertz would be used to represent the white level of a scene. In a typical playback system for such frequency modulated recorded video information, the frequency modulated signals are amplified and then limited and applied to a frequency demodulator which is responsive to the zero crossings of the limited output so as to provide a constant pulse width each time the zero axis is crossed. Thus a pulse train of constant pulse width pulses is provided whose pulse repetition rate varies according to the frequency of the FM signals. Accordingly, higher frequencies will provide more closely spaced pulses while lower frequencies will provide more widely spaced pulses. The pulse train is applied to a phase-corrected, low-pass video filter which provides as its output a voltage proportional to the average value of the pulse train input waveform thereto. For recorded waveforms of high frequency, since the pulses are closely spaced, a high value average output is provided, while for lower frequencies, since the pulses are more widely spaced, a lower average value output is provided. The average values so provided are indicative of the original video information that had been recorded, with white being indicated by a low average value, black by a high average value and the various shades of gray having intermediate average values. It is necessary to utilize a phase-corrected, low-pass filter whose components are carefully selected and matched in order to obtain high quality video reproduction which is free from transient ringing. Such phase-corrected filters are expensive, and it would be highly desirable if such a filter could be eliminated from the playback system.

SUMMARY OF THE INVENTION

Broadly the present invention provides a frequency demodulation method and apparatus wherein a phase-corrected filter is not required and wherein the demodulation of FM signals is accomplished by storing potentials in response to selected half-periods of the FM signals and selecting one of the potentials which is indicative of the intelligence within the FM signals under consideration.

BRIEF DESCRIPTION OF THE DRAWING

FIG. 1 is a schematic block diagram of one embodiment of the present invention;

FIG. 2 is a waveform diagram including a series of curves utilized in explaining the operation of FIG. 1;

FIG. 3 is a block schematic diagram of another embodiment of the present invention;

FIG. 4 is a waveform diagram including a series of curves utilized in explaining the operation of the embodiment of FIG. 3;

FIG. 5 is a block diagram of another embodiment of the present invention; and

FIG. 6 is a waveform diagram including a series of curves utilized in explaining the operation of the embodiment of FIG. 5.

DESCRIPTION OF THE PREFERRED EMBODIMENTS

A. Two Capacitor Demodulator system—FIGS. 1 and 2

Referring to FIGS. 1 and FIG. 2, the system of FIG. 1 and the method of operation thereof will be considered with reference to the curve of FIG. 2 wherein the number and letter references within the parenthesis indicate wherein FIG. 1 the waveforms of the respective curves of FIG. 2 appear. In FIG. 1 a video recorder 10 is provided which includes a magnetic recording medium such as tape, disc or drum apparatus. Recorded within the video recorder 10 are frequency modulated signals wherein a carrier frequency is deviated in response to the amplitude of a video waveform. For example, deviations of the carrier frequency to higher frequencies may be considered to be in the black direction with the highest frequency deviation occurring at the maximum black level while frequency deviations of the carrier frequencies to lower frequencies may be considered to be toward the white direction with the lowest frequency deviation being at the maximum white level.

Curve 1 of FIG. 2 shows a waveform representation of the frequency modulated signal recorded in the video recorder 10, with the waveform being substantially sinusoidal. In curve 1 it can be seen that the signal on the left-half of the waveform is at a higher frequency than that of the right-half. For the purposes of example, assume that the left-half of the waveform is indicative of black while the right-half of the direction is indicative of white video information.

The output of the video recorder 10 is an electrical signal varying as shown in curve 1 in frequency and is applied to a limiter 12. The function of the limiter 12 is to limit the waveform or curve 1 to a constant amplitude in both positive and negative directions and also to provide rectangular pulse outputs having equal half-period times as compared to the half cycles of the sinusoidal waveform of curve 1. Note that the frequency of the signals represented in curves 1 and 2 is the same and the curves cross the zero axis at the same time.

The output of limiter 12 is shown in curve 2 is applied to a phase splitter 14 wherein the phase thereof is split to provide the opposite phase waveforms as shown in curves 3a and 3b of FIG. 2. In other words, when the curve 3a is at a ONE output level the curve 3b is at a ZERO output level and vice versa. It should however be noted that the curves 3a and 3b have the same frequency as curves 1 and 2 and the same zero crossing times.

The outputs of the phase splitter 14 as shown in curves 3a and 3b are applied to a constant pulse width generator 16. The function of the constant pulse width generator is to sense when the waveforms of curves 3a and 3b change from a ZERO level to a ONE level and to provide a constant width pulse on response thereto respectively. These constant width pulses are shown in curves 4a and 4b, respectively, and are indicated to have a constant pulse width T. As an example of this a ONE level pulse 4a1 of curve 4a is initiated at a time t_1 by the constant pulse width generator 16 in response to a pulse 3a1 of curve (3a) changing from a ZERO to a ONE level with the pulse 4a1 terminating at a time t_2 when it reaches a pulse width T. The pulse 4a1 will have the constant pulse width T regardless of how long the pulse 3a1 remains at the ONE level. Similarly when a pulse 3b1 in curve 3b goes from a ZERO to a ONE level, a pulse 4b1 in curve 4b is initiated by the constant pulse width generator 16 and continues for a constant pulse width T before being terminated.

The two outputs shown in curves 4a and 4b of the constant pulse width generator 16 are applied to a flip-flop 18 which changes output states in response to the constant pulse width pulses applied respectively to the two inputs thereof. For example, the pulse 4a1 causes the flip-flop 18 to provide a ONE output at its 5 output and a complementary ZERO output at its $\bar{5}$ output. The outputs of the flip-flop 18 are shown in curves 5 and $\bar{5}$ of FIG. 2. The pulse 4b1 causes the flip-flop 18 to change its output state so that a ZERO is provided at the 5 output and a ONE at the complementary $\bar{5}$ output.

The $\bar{5}$ output of flip-flop 18 is applied to a logic circuit 20a and the 5 output of the flip-flop 18 is applied to a logic circuit 20b. The logic circuits 20a and 20b also receive the outputs 4a and 4b of the constant pulse width generator 16. The logic circuits 20a and 20b in the present example perform the NOR logic function, that is, when all three of the inputs thereto are at ZERO levels, a ONE output will be provided from the outputs 6a and 6b, respectively thereof. The outputs of the logic circuits 20a and 20b are utilized to control gaining amplifiers 22a and 22b respectively. When the logic circuit 20a provides a ONE output at its output 6a, the gating amplifier 22a is turned on to provide a conductive path therethrough so that a constant current source 24a is connected to an integrating capacitor Ca which is connected across the output of the gating amplifier 22a. As long as the gating amplifier 22a is turned on, the capacitor Ca will charge linearly from the constant current source 24a. When the output of the logic current 20a goes to ZERO, the gating amplifier 22a is turned off blocking the constant current source 24a from charging the capacitor C2. Similarly to this, a ONE output from the logic circuit 20b turns on a gating amplifier 22b so that an integrating capacitor Cb is charged from a constant current source 24b. When the output 6b of the logic circuit 20b is a ZERO, the gating amplifier 22b is turned off to block the constant current source 24b from charging the capacitor Cb.

The discharge of the capacitor Ca and the capacitor Cb is accomplished by discharge circuits which include the transistor Qa and differentiator 26a for the capacitor Ca and the transistor Qb and the differentiator 26b for the capacitor Cb. The differentiator 26a receives the output 32 of the phase splitter 14 and differentiates it to provide a spike output such as shown in curve 7a when the 3a input thereto changes from a ZERO to a ONE level. The spike output of the differentiator 26a is applied to the base electrode of the transistor Qa thereby turning on this transistor to discharge the capacitor Ca through the collector-emitter circuit thereof to ground. Similarly, the differentiator 26b differentiates the output 3b of the phase splitter 14 to provide a spike output as shown in curve 7b in response to the output 3b going from a ZERO to a ONE level. The spike output of the differentiator 26b is applied to the base of transistor Qb to turn on this transistor and provide a discharge path through the collector-emitter circuit thereof to discharge the capacitor Cb.

Referring to curve 8 of the FIG. 2, which is a composite waveform diagram of the voltages developed across the capacitors Ca and Cb, respectively, the voltage across the capacitor Ca is shown as a solid line and is designated 8a, and the voltage across the Cb is shown by a dashed line and indicated as 8b. At the time t1, in the example as shown in curve 8, the capacitor Ca is in a discharged state, at ground level, and the capacitor Cb is charged to a voltage Vb1. The charging cycle for the capacitor Ca is commenced at the time t1 with a pulse 6a1 being supplied to the gating amplifier 22a from the logic circuit 20. The pulse 6a1 is provided since at this time as can be seen by curves 4a, 4b and $\bar{5}$ of FIG. 2, the logic circuit 20a receives ZERO inputs from outputs 4a and 4b of the constant pulse width generator 16 and the $\bar{5}$ output of the flip-flop 18. At the time t1 constant constant pulse width pulse 4a1 is terminating while the constant pulse width pulse 4b1 does not commence until a later time t2. Thus, with the flip-flop 18 providing a ZERO output from the $\bar{5}$ output thereof, the logic circuit 20a provides a ONE output pulse 6a1 as shown in curve 6a to the gating amplifier 22a which causes the capacitor Ca to be charged linearly from the constant cur-

rent source 24a as shown by the solid curve in curve 8a between the times t1 and t2.

The charging of the capacitor Ca is terminated at the time t2 in that the pulse 4b1 occurs at the time t2 causing the logic circuit 20a to revert to a ZERO output state at the output 6a, which turns off the gating amplifier 22a. The voltage across the capacitor Ca remains at the level Vb1 as shown in curve 8a.

At the time t2, when the pulse 3b1 instigates the generation of the constant width pulse 4b1 the pulse 3b1 is differentiated by the differentiator 26b to provide the spike pulse 7b1 as shown in curve 7b. The pulse 7b1 turns on the transistor Q6 thereby discharging the capacitor Cb from its previously charged voltage of Vb1 to a ground potential at a time t3. Thus at the time t3 the capacitor Ca is charged to a voltage Vb1 and the capacitor Cb is discharged to ground potential.

The voltage outputs from the capacitors Ca and Cb are applied to an auctioneering circuit 28 which selects the higher voltage of the two. Hence, during the times t0 to t2 the auctioneering circuit 28 would select the voltage Vb1 as shown in curve 8b and between the time t2 until the capacitor Ca is discharged the auctioneering circuit 28 will select the voltage Vb1 from the capacitor Ca. The output of the auctioneering circuit 28 is shown in curve 9 of FIG. 2. The output of 9 of the auctioneering circuit 28 is the demodulated video output and is indicative of the intelligence as originally modulated and recorded in the frequency modulated signal such as shown in curve 1. As indicated on curve 9, for the time under consideration, for the voltage levels Vb1 and Vb2, a black output is provided by the curve 9 corresponding to the relatively high frequency of the FM signal of curve 1 during this time.

The charging of the capacitor Cb begins at a time t4 when the constant pulse width pulse 4b, terminates after a constant pulse width T. At the time t4 ZERO inputs are provided to the logic circuit 20b from the constant pulse generator 16 at outputs 4a and 4b and also from the flip-flop 18 output 5. The logic circuit 20b thus supplies a ONE output 6b1 as shown in curve 6b to turn on the gating amplifier 22b. The gating on of the gating amplifier 22b connects the constant current source 24b to the capacitor Cb thereby causing the capacitor Cb to be charged linearly as shown in curve 8b between the times t4 and t5. At the time t5 the charging of the capacitor Cb is terminated since the constant pulse width pulse 4a2 appears at this time being instigated in response to the pulse 3a2 being applied to the input of the constant pulse width generator 16. At the time t5 the logic circuit 20b thus outputs a ZERO to the gating amplifier 22b turning it off and disconnecting the constant current source 24b from the capacitor Cb. The capacitor Cb at the time t5 is charged to a voltage Vb2 which is indicated in curve 8b and is substantially equal to the voltage Vb1.

At the present time t5 the discharge of the capacitor Ca is also instigated in that the pulse 3a2 is also supplied to a differentiator 26a which supplies a spike output pulse 7a1 that is applied to the transistor Qa turning on this transistor and discharging the capacitor Ca therethrough from the voltage level Vb1 to a ground potential. During the time interval t5 to t6 the auctioneering circuit 28 will output the voltage Vb2 being the higher of the two voltages applied thereto during this time period. In curve 9 the output of the auctioneering circuit 28 still remains at the black level since the curve 1 is still at the same high frequency level.

It should be noted that the magnitude of the voltages curves 8a and 8b to which the capacitor Ca and Cb charge are directly proportional to each half period of the frequency modulated waveform of curve a and the waveform of curve b. This may be seen in that the capacitors Ca and Cb are only permitted to charge for the time period between constant pulse width pulses as shown in curves 4a and 4b. Accordingly, the capacitor Ca is charged between the times t1 and t2 with the pulse 4a1 terminating the time t1 and the pulse 4b1 beginning at the time t2. Since the pulse 4a1 has a constant pulse width T, the magnitude of voltage Vb1 to which the capacitor Ca charges is directly related to the half-period time t0 to t2 for the

waveforms of curves 1, 2 and 3a. Similarly the capacitor C_b is permitted to charge between the times t_2 and t_6 with the constant pulse 4b1 terminating at the time t_2 and the constant pulse width pulse 4a2 beginning at the time t_4 . Hence the magnitude of voltage V_{b2} to which the capacitor C_2 is permitted to charge is directly related to the half-period time t_2 to t_5 for the curves 1, 2 and 3b. In other words, the present demodulation system and method converts the time length of each half period of the FM signals into corresponding voltage levels.

The demodulated video output as shown in curve 9 will remain at the black level as indicated until the frequency of the recorded frequency modulated signal as shown in curve 1 changes. Until this change occurs the demodulation operation will continue as described with the magnitude to which the capacitors C_a and C_b charge being determined by the time period between the respective generation of the constant pulse width pulses of the curves 4a and 4b.

Considering now a later time t_7 when the frequency of the FM signal of curve 1 decreases being indicative that white information is included in the FM waveform. At the time t_7 a constant pulse width pulse 4b2 terminates after having been initiated a time period T previously in response to a pulse 3b2 as shown in curve 3b. With the termination of the pulse 4b2, ZERO input signals are provided to the logic circuit 20b from the inputs (4a, 4b and 5 causing the logic circuit 20b to output a pulse 6b2 to the gating amplifier 22b which instigates the charging cycle of the capacitor C_b from the constant current source 24b. The capacitor C_b charges linearly as shown in curve 8b from the time t_7 to a time t_8 . The linear charging of the capacitor C_b continues until the time t_8 to a voltage level V_{b3} which is higher than the previous voltage level V_{b1} and V_{b2} . This is due to the fact that the charging of the capacitor C_b continues until the time t_8 until a constant pulse width pulse 4b3 is generated in response to the appearance of a pulse 3a3 from the phase splitter 14 indicating the beginning of a new half-period of the recorded waveform of curve 1. The generation of the pulse 4a3 causes the logic circuit 20b to output a ZERO thereby turning off the gating amplifier 22b and terminating the charging cycle of the capacitor C_b .

It should be noted that the charging cycle for the capacitor C_b from t_7 to t_8 in the present example is shown to be twice as long as the previous charging cycles for the capacitor C_b from T_4 to T_5 . Thus the capacitor C_b is charged to a voltage V_{b3} which is twice the value of the voltages V_{b1} and V_{b2} . The magnitude of the voltage to which the capacitor C_b charges is directly dependent upon when the next half-period of the waveforms 1 and 2 appear to terminate the charging cycle. The lower the frequency of the waveforms 1 and 2 the higher the value of the charging voltage on the capacitor C_b .

At the time t_8 the capacitor C_a having been previously charged to a voltage level V_{a2} equal to the voltage level V_{a1} , V_{b1} , V_{b2} , is discharged in response to a spike pulse 7a2 being applied to the transistor Q_a with the capacitor C_a discharging to a ground potential. The auctioneering circuit 20a is responsive to the output the larger of the two input voltages 8a and 8b thereto and therefore when the voltage of curve 8b exceeds the voltage of the curve 8a somewhere between the time t_7 and t_8 the output of the auctioneering circuit 20a will increase as shown in curve 9 to correspond to the voltage level V_{b3} as stored in the capacitor C_b . As indicated on curve (9) the voltage corresponding to the voltage V_{b3} is indicative of a white level of video intelligence.

At a time t_9 when the constant pulse width pulse 4a3 terminates, the logic of the circuit 20A supplies a ONE output pulse 6a2 to the gating amplifier 22a which instigates the charging cycle for the capacitor C_a to be charged linearly from the constant current source 24a as shown in curve (8a) between the times t_9 and t_{10} . At the time t_{10} a constant pulse width pulse 4b3 is supplied to the logic circuit 20a thereby terminating the pulse 6a2 which turns off the gating amplifier 22a with the capacitor C_a storing a voltage V_{a3} which is equal to the voltage V_{b3} . At the time t_{10} a spike voltage pulse 7b2 is ap-

plied to the transistor Q_b causing the capacitor C_b to discharge to ground potential. The auctioneering circuit 28 selects the higher of the two voltages which is the voltage V_{a3} and supplies a demodulated video output as shown in curve 9 at the white level. The operation of the demodulating system hence continues as described at the white level as long as the frequency of the recorded FM signal remains at the low frequency level corresponding to white video intelligence. The described demodulating system of course responds to video information in the gray level between the black and white levels with the charging times for the respective integrating capacitors C_a and C_b being determined by the time duration of each half period of the recorded FM signals. The demodulated video output 9 provided is a reconstruction of the original video information that had been utilized to frequency modulate the carrier frequency for recording. This demodulated output 9 is provided without the need of a phase-corrected, low-pass filter as was required in the prior art and thus provides substantial cost advantages over prior art systems.

B. Four Capacitor Demodulating System—FIGS. 3 and 4

Another embodiment of the present invention is shown in FIG. 3 and is operative to change the time duration of the half-periods of a frequency modulated waveform into a corresponding voltage level which is indicative of the original video intelligence. Corresponding circuit functions in FIGS. 3 will be designated with the same reference characters as those in FIG. 1. Also curves 1 and 2 of FIG. 4 are substantially identical to curves 1 and 2 of FIG. 2, respectively. 78 81 in 84 30 1 the video recorder 10 provides the output curve 1 to a limiter 12 which supplies the output waveform of curve 2. The individual half cycles of curve 2 of FIG. 4 are designated P1, P2, P3 and P4 for four successive half-periods thereof. The output 2 of the limiter 12 is applied to a four-phase phase splitter 14' which supplies as outputs thereof pulses P1, P2, P3 and P4 as shown in the curves 2 of FIG. 4 and also the complements of these signals, respectively, $\bar{P}_1$, $\bar{P}_2$, $\bar{P}_3$, $\bar{P}_4$. The outputs P1, P2, P3 and P4 of the four-phase phase splitter 14' are applied to gating amplifiers G1, G2, G3 and G4, respectively. 40 The gating amplifiers G1, G2, G3 and G4 correspond to the gating amplifiers 22a and 22b of FIG. 1 as to their function. In response to the pulses P1, P2, P3 and P4, respectively, gating amplifiers G1, G2, G3 and G4 are turned on to provide a charging plan therethrough from a constant current source 24 to charge the capacitors C1, C2, C3 and C4, respectively. The charging operation of the respective capacitors C1, C2, C3 and C4 is terminated when the pulses P1, P2, P3, P4 reverse phase, respectively.

50 The complementary outputs $\bar{P}_3$, $\bar{P}_4$, $\bar{P}_1$ and $\bar{P}_2$ of the four-phase splitter 14' are applied, respectively, to discharge circuits D1, D2, D3 and D4. The discharge circuits D1, D2, D3 and D4 correspond in function to the transistors Q_a and Q_b of FIG. 1 but have only been shown schematically in FIG. 3 for the purpose of simplicity and clarity. The capacitor C1 is charged via the gating amplifier G1 from the current source 24 during the time period t_0 to t_1 when the pulse P1 is at its positive polarity. The capacitor C1 charges to a voltage V1 as shown in the solid curve 3-1 of FIG. 4 and remains there until the time t_2 when the complementary output $\bar{P}_3$ will be at a negative polarity to cause the discharge circuit D1 to discharge the capacitor C1 therethrough to a ground potential at time t_3 as shown in curve 3-1. The capacitor C1 remains discharged through the time t_3 to time t_4 when its charging cycle is initiated to be charged to the voltage V1 again at the time t_5 .

70 The other capacitors C2, C3 and C4 are respectively charged and discharged in a similar fashion to the capacitor C1 during their respective charging and discharging times as better shown in the composite curves of curve 3 wherein the dashed curve 3-2 is indicative of 3 voltage on the capacitor C2, the dash-dot curve 3-3 is indicative of the voltage on the capacitor C3 and the dotted curve 3-4 is indicative of the voltage on the capacitor C4. From curve 3 it can be seen that the capacitor C2 is charged during the time period t_1 to t_2 main-

tained in its charged state until the time t_3 and discharged during the time period t_3-t_4 . The capacitor C_3 is discharged during time t_0-t_1 , charged during the time t_3-t_4 , maintained at its charged level during the times t_2-t_3 and discharged again during the time t_4-t_5 . The capacitor C_4 is discharged during the time period t_1-t_2 , maintained in a discharged state during the time period t_2-t_3 and charged during the time period t_3-t_4 to store this charge during the timer period t_4-t_5 .

The voltage represented in curves 4-1, 4-2, 4-3 and 4-4 are applied to an auctioneering circuit 28' which selects the highest of these voltages to provide a video output as shown in curve 4 of FIG. 4. Thus during the time period t_1-t_2 the voltage V_1 on the capacitor C_1 is selected and during the times t_2-t_3 , t_3-t_4 , and t_4-t_5 , the voltage on capacitors C_2 , C_3 and C_4 are respectively selected by the auctioneering circuit 28' to provide a demodulated video output as shown in curve 5 indicative of black intelligence in the originally recorded frequency modulated signal of curve 1 of FIG. 4. When the frequency of the recorded waveform of curve 1 drops to indicate a white level at the time t_5 , the capacitor C_2 is permitted to charge a higher voltage level V_2 as determined by the length of the half-period P_2' as shown in curve 2. The capacitor C_2 thus charges linearly to the voltage V_2 until a time t_6 when the pulse P_2' changes polarity. The operation of the demodulating system then continues as described with each of the capacitors C_3 , C_4 , C_1 ... being charged to the voltage V_2 , storing that voltage and being discharged in the sequence as described above.

The auctioneering circuit 28' selects the highest voltage applied thereto from the particular capacitor C_1 , C_2 , C_3 and C_4 , and outputs this voltage as shown in curve 4 of FIG. 4 which as indicated after the time t_6 corresponds to a white level of intelligence in the FM signal shown in curve (1).

Thus, the four capacitor system of FIG. 3, the frequency deviations of the originally recorded intelligence are converted into voltage levels corresponding to the original video intelligence. The use of the four capacitor system of FIG. 3 permits a longer time for the discharge of the various capacitors since the capacitor is charged only once every four half-periods rather than every other half-period as in the system of FIG. 1. However this is done at the expense of the additional capacitors and circuitry.

C. Two Capacitor Sampling Demodulator System—FIGS. 5 and 6

A two capacitor demodulating system is shown in FIG. 5 wherein a sampling technique is utilized. Components performing similar functions to the systems of FIGS. 1 and 3 are similarly designated in FIG. 5. The output of the video recorder 10 and the limiter 12 are identical as shown in the curves 1 and 2 respectively of FIGS. 2 and 4. For convenience curve 2 has been reproduced in FIG. 6 to act as a time reference in illustrating the demodulating operation of FIG. 5. The output of the limiter 2 is applied to a phase splitter 14 which is identical to that of FIG. 1 which applies outputs 3a and 3b as shown in curves 3a and 3b of FIG. 2 respectively. At the time t_0 as shown in FIG. 6, which is the beginning of the half-period pulse P_1 of curve 2, the gating amplifier 22a is turned on to connect the current source 24a to the integrating capacitor C_a . The capacitor C_a charges linearly until the time t_1 at the end of the pulse P_1 . At this time the gating amplifier 22a is turned off to terminate the charging of the capacitor C_a . The (3b) output from the phase splitter 14 is also applied to the differentiator 26a which supplies in response thereto a spike sampling pulse output such as shown in curve 7a of FIG. 2. The spike pulse from the differentiator 26a turns on a sampling switch S_a which samples the voltage level V_a appearing on the capacitor C_a at this time. The voltage V_a is translated through the sampling switch S_a to a holding circuit 30. The sampling operation occurs at a time t_2 shortly after the time t_1 being delayed slightly by the time delays of the differentiator 26 and the sampling switch S_a . After the relatively short duration of the spike sampling pulse 7a, the sampling switch S_a is opened again at the termination thereof. However, the holding

circuit 30 retains the voltage level V_a until new input information is supplied thereto. The output of the holding circuit 30 is thus sampled voltage V_a which corresponds to the demodulated output as shown in curve 9 of FIG. 2.

5 The differentiated output 7ais also applied to a delay circuit 32a which delays the signal for a period of time t_3 minus t_2 . The time t_3 is the reset time for the capacitor C_a , and at this time the delay 32a supplies a pulse to the discharge circuit 2a which provides a discharge path to ground therethrough for 10 the capacitor C_a resetting it to ground potential. The capacitor C_a has been discharged to ground at the time t_4 so that it is in condition to begin recharging at a time t_5 whenever the next positive polarity pulse P_3 occurs.

Now considering the capacitor C_b , at time t_1 when the 15 charging cycle of the capacitor C_a has terminated capacitor C_b begins its linear charging cycle from the current source 24b since the gating amplifier 22b is gated on in response to the output 3b of the phase splitter 14 at this time. The capacitor C_b continues to be charged until the time t_5 when the pulse P_2 20 terminates thereby turning off the gating amplifier 22b. The 3a output of the phase splitter 14 is also applied to the differentiator 26b wherein it is differentiated to provide a spike sampling pulse output such as shown in curve 7b of FIG. 2. The spike pulse is applied to a sampling switch S_b to turn it on 25 translate thereto the voltage V_b appearing on the capacitor C_b at the sampling time indicated as the time t_6 in FIG. 6. After the termination of the spike pulse input to the sampling switch S_b , the switch is again opened. However, the holding circuit 30 maintains the voltage level V_b until the input thereto is 30 changed. The output V_b of the holding circuit 30 at this time is the demodulated output indicative of the input modulation of the FM signal.

The spike pulse output (7b of the differentiator 26b is also 35 supplied to a delay circuit 32b where it is delayed for a time t_7 minus t_6 and then supplied to a discharge circuit V_b . The turning on of the discharge circuit V_b causes the capacitor C_b to be discharged therethrough to ground potential at a time t_8 . The capacitor C_b is thus reset for the next cycle of operation.

40 The operation of FIG. 5 continues as described. If the frequency of the FM signals such as shown in curve 1 of FIG. 2 should increase each of the capacitors C_a and C_b will charge to a higher voltage directly in response to the half-period at the decreased frequency. This higher voltage will then be sampled by the sampling switches S_a and S_b , respectively, and be held within the holding circuit 30 to be outputted as the demodulated video information of the system.

45 In summary, all three embodiments described herein shown in FIGS. 1, 3 and 5 provide demodulated video outputs 50 without the requirement for phase-corrected, low-pass filters by providing a potential which is proportional to the half-period of the FM signal under consideration. Only two and four capacitor systems have been shown however it should be understood that the use of other numbers of capacitors, e.g. 3, 55 5, etc., is deemed to be within the scope of the present invention.

55 Some residual FM carrier related ripple frequency components may be present at low amplitude in the output signal due to a slight mismatch on component values or time delays. 60 Although small in amplitude they may be discernable in the video output. The use of the high frequency preemphasis of the video prior to FM modulation and recording with corresponding deemphasis following the demodulation techniques described above as beneficial to provide additional 65 attenuation of any residual carrier related ripple components.

I claim as my invention:

1. An FM demodulator system operative with FM signals comprising:
means for storing a plurality of potentials in response to selected half-periods of said FM signals;
means for selecting one of said potentials from those stored which is indicative of the intelligence in said FM signals;
and
means for selectively removing each of said plurality of potentials from said means for storing.

2. The system of claim 1 wherein:
each of said plurality of potentials stored being proportional
to each of said half-periods respectively.
3. The system of claim 2 wherein:
said means for storing includes a plurality of capacitive
devices, and means for charging each of said capacitive
devices respectively in response to each of said half-
periods.
4. The system of claim 3 wherein:
each of said plurality potentials is stored on said plurality of
capacitive devices respectively at least until said means
for selecting has selected said one potential.
5. The system of claim 4 wherein:
said plurality of capacitive devices includes first and second
capacitive devices,
said plurality of charging means includes first and second
charging means for charging said first and second capaci-
tive devices respectively.
said first and second capacitive devices being respectively
charged to first and second of said plurality of potentials
proportional to first and second of said half-periods, said
first and second half-periods being successive half-
periods of said FM signals,
said means for selecting selects said one potential from said
first and second potential depending upon the relative
magnitudes at a given time.
6. The system of claim 5 wherein:
said plurality of capacitive devices includes third and fourth
capacitive devices,
said plurality of charging means includes third and fourth
charging means for charging said third and fourth capaci-
tive devices respectively,
said third and fourth capacitive devices being charged to
third and fourth of said plurality of potentials respectively
proportional to third and fourth half-periods of said FM
signals, said third and fourth half-periods respectively
being the subsequent half-periods to said first and second
half-periods,
means for selecting selects said one potential from said first,
second, third and fourth potentials depending upon the

- relative magnitudes thereof at a given time.
7. The system of claim 4 wherein:
said one potential being stored in one of said capacitive
devices during a given half-period while another of said
capacitive devices being charged to the next of said plu-
rality of potentials indicative of said intelligence in said
FM signals.
8. The system of claim 4 wherein:
said means of selecting includes means for sampling each of
said plurality of potentials and holding that potential at
said one potential until said means for removing each of
said potentials has operated.
9. A method of demodulating FM signals comprising the
steps of:
15 storing a plurality of potentials in response to selective half
periods of said FM signals,
selecting one of said potentials from those stores which is in-
dicative of the intelligence in said FM signals; and
removing selectively each of said potentials which have
been stored.
10. The method of claim 9 wherein:
each of said plurality of potentials stored being proportional
to each of said half-periods respectively.
11. The method of claim 10 includes
25 selectively charging a plurality of storage means to said plu-
rality of potentials respectively,
said one of said plurality of potentials being stored in one of
said storage means during a half-period during which
another of said storage means is being charged to the next
one of said plurality of potentials indicative of said intel-
ligence in said FM signals.
12. The method of claim 11 wherein:
said steps of selecting said one of said plurality of potentials
includes sampling each of said plurality of potentials and
holding that potentials as said one potential until
removed.
13. The method the method of claim 11 wherein:
said step of selecting includes selecting said one potential
depending upon the relative magnitude of said plurality of
potentials dueing a given time.
